N. J. JEFFRIES.
ANTENNA FOR WIRELESS TELEGRAPHY.
APPLICATION FILED MAY 8, 1913.

1,106,945.

Patented Aug. 11, 1914

UNITED STATES PATENT OFFICE

NICHOLAS J. JEFFRIES, OF ATLANTIC CITY, NEW JERSEY.

ANTENNA FOR WIRELESS TELEGRAPHY.

1,106,945.

Specification of Letters Patent. Patented Aug. 11, 1914.

Application filed May 8, 1913. Serial No. 766,290.

To all whom it may concern:

Be it known that I, NICHOLAS J. JEFFRIES, a citizen of the United States of America, and resident of Atlantic City, in the county of Atlantic and State of New Jersey, have invented certain new and useful Improvements in Antennæ for Wireless Telegraphy, of which the following is a specification.

This invention relates to certain new and useful improvements in antennæ for wireless telegraphy, and it has for its objects among others to provide a simple, novel, yet efficient form of antenna, which shall be portable, collapsible and extensible, of minimum weight and easily carried and handled and put up into operative position.

The antenna may be employed as either a transmitter or a receiver and can be maintained in any desired position without any special support. It may be quickly hung from the limb of a tree or any other object and as easily taken down and collapsed for transportation or storage.

Other objects and advantages of the invention will hereinafter appear and the novel features thereof will be specifically defined by the appended claims.

The invention is capable of embodiment in a variety of forms, the preferable one only of which is herein illustrated. This form is clearly shown in the accompanying drawings, which, with the numerals of reference marked thereon, form a part of this specification, and in which—

Figure 1 is an elevation of the antenna partially extended. Fig. 2 is an end view thereof. Fig. 3 is an edge view showing the antenna collapsed ready for transportation or storage. Fig. 4 is an enlarged fragmentary detail showing the antenna partially collapsed. Fig. 5 is an enlarged detail in elevation.

Like numerals of reference indicate like parts throughout the several views.

Referring to the drawings 1 designates an end portion, of which there are two, and these ends may be of any suitable form of construction and material. In the present instance each head consists of a plurality of radiating arms 2 joined in any way, or made integral, at the center. The antenna may be of any desired length.

3 are members, flexible but non-elastic to any great extent, and may be formed for instance of oil-silk or analogous substance. They pass loosely through openings 4 in

the arms 2, as seen best in Fig. 4 and their ends are connected to insulators 5 of known or any approved form of construction. As seen in Fig. 2 the members 3 extend inclinedly so as to attach to the insulators at the axial center of the antenna, as seen clearly in Fig. 1.

6 is the antenna wire of suitable nature; it is wound spirally extending lengthwise of the antenna, one end being attached in any suitable manner to one end 1 of the antenna as seen at 7 the other end 8 being free and designed to lead to the instruments in the operating-room. The wire 6 is attached to the members 3 wherever they intersect as shown at 9.

Thus constructed, the antenna may be collapsed into small compass as seen in Fig. 3. When it is desired to use the same it may be supported or suspended in any suitable manner, in any desired place. By attaching a rope to one of the insulators, and throwing the rope over the limb of a tree, for instance, the antenna may be quickly hauled up and put into immediate use. It is easily carried about and requires no special skill in setting it up or collapsing it.

Modifications in detail may be resorted to without departing from the spirit of the invention or sacrificing any of its advantages.

What is claimed as new is:—

1. A portable collapsible antenna comprising end members, spiral antenna wire compressible between said end members, and supporting means connected to said antenna wire and slidably associated with said end members.

2. A portable collapsible antenna for wireless telegraphy comprising end members movable toward and from each other, antenna wire spirally arranged between said end members, and means for supporting said antenna connected to said wire and loosely slidably associated with said end members.

3. A portable collapsible antenna for wireless telegraphy comprising relatively movable end members, wire disposed between said end members, and means for supporting said antenna movable through the end members and attached to said wire and provided at the free ends with insulators.

4. An antenna for wireless telegraphy

comprising end supports, flexible means for supporting said antenna passed loosely therethrough, wire wound around and connected to said means, and insulators connected to the ends of said means.

5. An antenna for wireless telegraphy comprising end supports movable toward and from each other, flexible members passed loosely through said supports and adapted for the attachment of the antenna,

and wire wound around said flexible members and attached thereto, said wire and flexible members being designed to be forced together between the end supports.

Signed by me at Washington, D. C. this 15
8th day of May 1913.

NICHOLAS J. JEFFRIES.
